Inventor
Ira I. Rush,

By *E. C. Groaman, Jr.*
His Attorney

UNITED STATES PATENT OFFICE.

IRA I. RUSH, OF PERU, INDIANA.

GAS MIXER.

Application filed February 21, 1922. Serial No. 538,268.

To all whom it may concern:

Be it known that I, IRA I. RUSH, a citizen of the United States, residing at Peru, in the county of Miami and State of Indiana, have invented certain new and useful Improvements in Gas Mixers, of which the following is a specification, reference being had therein to the accompanying drawings.

This invention relates to a gas mixer, and 10 the object of the invention is the construction of a simple and efficient device to be placed between the carburettor and the intake of the gasoline motor, which will result in the efficient operation of the motor, at a 15 minimum expense.

With this and other objects in view, my invention comprises certain novel combinations, constructions and arrangements of parts as will be hereinafter described, illustrated in the accompanying drawings, and more particularly pointed out in the appended claim.

In the drawings:

Figure 1 is a front view, in elevation, of 25 a device constructed in accordance with the present invention.

Figure 2 is a sectional view taken on line 2-2, Fig. 1, and looking in the direction of the arrows.

Figure 3 is a top plan view of the device.

Figure 4 is a sectional view taken on line 4-4, Fig. 1, and looking in the direction of the arrows.

Referring to the drawings by numerals, 35 1 designates the body-casing which is provided near its ends with apertures 2 that are adapted to receive the bolts for fastening the device between the carburettor and the intake.

40 In the center of the body-casing is a large opening 3, and extending across opening 3, at one side of the body-casing 1, and having its ends counter-sunk in the body-casing, is a flat bar 4. This bar 4 is retained in position by screws 5. Integral with the bar 4, at its center, is a stub shaft 6. On the outer end of shaft 6 is formed an integral head 7. Between bar 4 and head 7, and mounted on stub shaft 6, is a propeller 8 consisting of a 45 hub and blades.

A valve opening 9 is formed in the top of the body-casing 1 (Fig. 4) and across the

outer end of valve opening 1 I place a detachable plate 10 having an opening 11. A valve device 12 is in valve opening 9 and 55 normally closes the opening 11 in plate 10 but when the motor is running, with my device attached thereto, air will enter through openings 11 and 9 and mingle with the gasoline that is passing from the carburettor through opening 3 into the intake of the motor. My propeller 8 will be automatically rotated by the suction of the motor, causing the gases to be broken up in small particles, and my device will "sweep" 60 the intake channel dry thus preventing gasoline in its crude state from entering the cylinders of the motor.

I claim that by use of my device, a saving of 33½% of gasoline is obtained; 30% more 70 speed and power is obtained at the same time, preventing the fouling of pistons and spark plugs too.

While I have described the preferred embodiment of my invention, and have illustrated the same in the accompanying drawings, certain minor changes or alterations may appear to one skilled in the art to which this invention relates, during the extensive manufacture of the same and I, 75 therefore, reserve the right to make such alterations or changes as shall fairly fall within the scope of the appended claim.

What I claim is:

A gas mixer comprising a flat body having 85 a fluid passage intermediate its length and fastener receiving openings in its end portions, a fan rotatably mounted in the opening, said body being provided with a port leading from its edge face and communicating with the fluid passage at the periphery thereof, the edge face of the body being provided with a recess forming a seat about the outer end of said port, a cover plate for said port fitting in said seat and having an 90 air passage of less diameter than said port, removable fastener screws passing through said plate, and an inwardly opening spring controlled valve in said port normally held in closing engagement with the inner end 95 of the air passage of said plate.

In testimony whereof I hereunto affix my signature.

IRA I. RUSH.
